ELECTRIC IGNITION GENERATOR

Ludvig P. Kongsted, Longmeadow, Mass., assignor
to United American Bosch Corporation, Spring-
field, Mass., a corporation of New York

Application February 13, 1937, Serial No. 125,540

9 Claims. (Cl. 171—209)

This invention relates to electric generators for ignition circuits, and particularly to one of simple and inexpensive construction for high speed operation of multicylinder internal combustion engines.

Magneton for use with high speed multicylinder engines have usually employed permanent magnets, but on account of the time delay in the magnetic saturation of the generating winding thereof, the voltage and energy delivered is insufficient for reliable ignition at the extremely high engine speeds now prevalent or desired, particularly with high compression engines, with the result that the speed or the compression ratio, or both, were kept below the value desired. Externally excited electromagnets have been used to replace or reinforce the permanent magnets, but in these magnetos also, the delay in magnetic saturation has limited the output of the magneto below present requirements due in part to the ineffectiveness of the external excitation to bring about a sufficiently rapid rate of flux reversal of sufficiently large amplitude through the generating winding.

In accordance with my invention the foregoing disadvantages are overcome and satisfactory sparking obtained at higher continuous speeds and higher compression ratio than heretofore possible, by arranging the magnetic circuit of the magneto in such manner that certain portions thereof are selected to bring about the conduction of magnetic flux through the core of the generating winding first in one direction and then in the other, with a reversal thereof that is extremely rapid between the limits of magnetization. In such a magnetic circuit, the time delay of magnetization of the core of the generating winding is reduced by externally excited electromagnets, preferably by means of a plurality of field coils in series, by arrangement or in effect, to boost or reinforce the magnetizing effect of each other and thereby bring about the reversal of flux through the core of the generating winding or ignition coil with greater rapidity and sharpness. In the preferred form of this magneto, advantage is taken of the fact that one or more of the alternative magnetizing paths may be periodically open circuited without weakening the strength thereof upon subsequently connecting it or them to the core of the generating winding or ignition coil.

The above and other objects and features of this invention will be more apparent to those skilled in the art from a consideration of the fol-

lowing detailed description taken in conjunction with the accompanying drawings in which:

Fig. 1 is a diagrammatic view showing the arrangement of mechanism and circuits of a magneto constructed in accordance with this invention and applicable to an eight-cylinder four-cycle internal combustion engine; Fig. 2 is a view similar to Fig. 1 of a modification applicable to a six-cylinder four-cycle engine; Fig. 3 is a further modification applicable to a four-cylinder four-cycle engine; Fig. 4 is a wiring diagram; Fig. 5 shows a longitudinal section through a magneto of the timer-distributor type having the magnetic circuit of Fig. 1; Fig. 6 is an end view of the same with parts removed to show the internal construction; and Fig. 7 is an alternative wiring diagram of the field circuit.

Referring to Fig. 1, reference numerals 1 and 2 indicate externally excited field coils for magnetizing the cores 3 and 4 respectively of the magneto. These cores are of laminated sheet steel of high permeability and otherwise well known characteristics and are provided with upwardly extending shanks 5 and 6 which are magnetically connected to the ends of the core 7 of the generating coil 8 comprising primary and secondary windings 8' and 8''. The core 3 also has pole pieces 9 and 10 extending inwardly from its upper and lower ends and similar pole pieces 11 and 12 are provided for core 4. The unmagnetized rotor 13 of similar laminations has four radial arms 14 which coact with the pole pieces 9, 10, 11, and 12 to alter the magnetic circuit therethrough in a manner which will be hereinafter more fully described. It will be observed at this point that all magnetic circuits are completely laminated including the flux generating elements 3 and 4 which differ in this important respect from the magnets of usual permanent magnet magnetos. The coils 1 and 2 are electrically connected in series with each other to a storage battery 15 through the ignition switch 16. The direction of current flow through the coils is such that the shanks 5 and 6, which are magnetically connected to opposite ends of the coil core 7, are of the same magnetic polarity, as indicated by N and S, the dotted letters indicating that the magnetic strength of the pole piece 10 and the pole piece 9 with shank 5 is less when the magnetic circuit thereof is opened at pole shoe 10 by the rotor than when closed later in the rotation.

Assuming switch 16 closed and rotor 13 turning clockwise as indicated by the arrow, when the parts are in the position shown in Fig. 1 with one of the rotor arms 14 adjacent pole piece 55

9 and the diametrically opposite arm adjacent pole piece 12, a magnetic circuit is provided from the north pole of core 4 by way of shank 6 and coil core 7 to shank 5, and thence by way of pole piece 9 through said arms of the rotor to pole piece 12 forming the south pole of core 4. When the rotor is in the dotted line position, or 45° from the former position, the path through core 4 is open and the path through core 3 is closed. 10 The magnetic circuit is now from the north pole of core 3 by way of shank 5 through core 7 and thence by way of shank 6 and pole piece 11 through diametrically opposite arms 14 of rotor 13 to the pole piece 10 forming the south pole of core 3. This reversal of the magnetic flux in core 7 occurs between the full and dotted line positions of rotor 13 at the instant each pair of diametrically opposed arms 14 passes into or out of cooperation with the pole pieces 9, 10, 11 and 12. At each of these instants, the reversal of flux in the core 7 is extremely rapid from its full value in one direction to its full value in the other direction. This reversal of flux at the extreme high time rate of change induces an unusually high voltage in the secondary winding 8'' of the generating coil at all speeds from a low speed in starting or at idling to a very high speed in operation, particularly since the interrupter 17 in the primary winding 8' of the generating coil is opened at the same instant. This rapid reversal is due in part to the completely laminated magnetic members in which the flux is generated and by which it is conducted. It is, however, more due to the arrangement by which the current in the field coil 2 of the core 4 then becoming active is boosted by the current generated in the other field coil 1 during reversal of the flux in the coil 7. This boosting effect results from the fact that the turns of the field coil 1 are then cut by the flux disappearing in its core 3 to thereby generate an electromotive force in the same direction as the electromotive force of the battery. The additional current resulting from this added electromotive force flows to the field coil 2 to increase at the instant the rapidity with which the flux is built up in its core 4. Without such a boosting effect of one field coil on the other, at each period of flux reversal, the flux established by the core then becoming active would increase at a reduced rate because the counter-electromotive force generated in it by the establishment of the flux through its core opposes that of the battery.

As a result of the fact that at each period of flux reversal the magnetic circuit through one of the cores 3 or 4 is open, the flux then passing through rotor 13 and also through the air gaps is that flux produced by only one field coil. This factor, resulting in lower flux densities in the air gap and pole pieces than would otherwise be the case, contributes to a still further increase in the rapidity of the flux reversal at each period of ignition. It will be noted that in a position intermediate those shown in full and dotted lines in Fig. 1 or as shown in Fig. 6, the magnetic circuits through both coil cores 3 and 4 are momentarily closed through adjacent rotor arms 14. This helps the flux through coil 1 build up and prevents the flux through coil 2 from falling 70 until the rotor approaches the position shown in dotted lines, during which period the magnetic circuit through the coil 2 is suddenly opened resulting in the previously noted boost in the current through coil 1.

75 The operation of the embodiments shown in

Figs. 2 and 3 will now be obvious to those skilled in the art. The same reference numerals have been applied to similar parts in each of the embodiments. Further modifications necessary to adapt the invention to provide magnetos serving any other number of cylinders of either two or four cycle engines will be apparent to those skilled in the art from a consideration of the forms shown.

Referring to Figs. 5 and 6, which illustrate a physical embodiment of my invention, the rotor 13 is fixed to the timer or cam shaft 18 which is rotatable in housing 19 having an endplate 20 and an integral internal partition 21 which provide suitable bearings for the shaft. The field coils 1 and 2 are positioned on the sides of the housing in non-magnetic cup-shaped protective covers 22 which may be readily detached from the housing 19 by screws 23. The cores 3 and 4 are held in position by spring brackets 24 riveted in the cup-shaped members. The shanks 5 and 6 extend through an upwardly projecting portion of the housing 19 and support the outer ends of core 7. The generating coil 8 is separately housed in a cylindrical insulating member 25 which projects into the upwardly extending portion of housing 19. Caps 26 hold the core 7 on shanks 5 and 6. A centrifugal governor 27 controls the timing of the interrupter cam 28 in the well known way. A plate 29, which is preferably adjustable manually or otherwise, carries the interrupter 17, capable of operation at sufficiently high speed, adjacent the cam 28. A distributor rotor 30, for a conventional distributor cap 31, is mounted on the outer end of cam 28.

From the foregoing description taken in conjunction with the accompanying drawings, it will be seen that I have provided a magneto structure in which a pair of externally excited magnets are alternately connected in magnetic circuit through the core of a generating coil in such manner that the magnetic flux through the generating coil is rapidly reversed, and that at the instant of reversal one of the externally excited field coils boosts the other field coil to thereby augment the rate of this flux reversal.

I have described the principles of operation of the invention in connection with the preferred form of the apparatus. It will be understood that the apparatus shown is merely illustrative and that changes may be made as desired by those skilled in the art within the scope of the appended claims. For instance, the magneto may have permanent magnets to replace or supplement the electromagnets. Also, the generating coil 8 may comprise a primary winding only for low tension ignition or for supplying interrupter currents to an outside high tension ignition coil in the well known way. Also this magneto may be arranged for ignition of two-cycle or other engines, and for ignition of engines of various types requiring sparks at irregular intervals. Also the magneto may be driven at other than cam-shaft speed, in which case distributor gearing may be necessary. Also the externally excited field coils may be connected in electrical parallel with each other and the beneficial effect of the series arrangement obtained by the use of a high reactance or transformer with center tap connected in the circuit between the battery and field coils, as for instance by coupling coil 32 shown in Fig. 7. In this arrangement the current enters the center tap of the transformer 32 and at standstill conditions the current divides equally between the two field circuits 1 and 2, and

the resultant magnetic flux in the transformer core is practically zero since the two fields oppose each other. During rotation of the magneto the flux pulsations in 1 and 2 which occur alternately will induce voltage and current pulsations which will tend to oppose the change in flux.

Thus assume for the moment that the flux through the core of 1 is collapsing. A voltage and current is immediately generated which tends to maintain the flux through 1. This increase in average field current through the branch circuit 1 will induce a voltage and current in the opposite direction in the other half of the transformer winding which will be in the same direction as the normal field current in 2, thus strengthening or reinforcing this circuit at the proper moment when an increase in flux must take place.

Having thus described the invention, what is claimed is:

1. In an externally excited ignition generator, a generating winding, externally excited field coils, a rotor for conducting magnetic flux from the field coils in reverse directions through the generating winding, means for closing the magnetic circuit from one field coil through the generating winding and opening the magnetic circuit from another field coil, and electrical connections for the field coils whereby a decrease in magnetic flux in one field coil induces a current which augments the current in the other field coil.

2. In an externally excited ignition generator, a generating winding, two externally excited field coils electrically connected in series, a rotor for conducting magnetic flux from the field coils in reverse directions through the generating winding, means for closing the magnetic circuit from one field coil through the generating winding and opening the magnetic circuit from another field coil, and electrical connections for the field coils whereby a decrease in magnetic flux in one field induces a current which augments the current in the other field coil.

3. In an externally excited ignition generator, a generating winding, two externally excited field coils electrically connected in parallel, a rotor for conducting magnetic flux from the field coils in reverse directions through the generating winding, means for closing the magnetic circuit from one field coil through the generating winding and opening the magnetic circuit from another field coil, and a mutual inductance in the electrical circuit of the field coils whereby a decrease in magnetic flux in one field induces a current which augments the current in the other field coil.

4. In an externally excited generator, a generating winding, two externally excited field coils, means for alternately conducting magnetic flux from one exciting coil in one direction through the generating winding and for conducting magnetic flux from the other field coil in the reverse direction through the generating winding, and electrical connections for said field coils so arranged that the decline of the magnetic flux through one field coil boosts the current through the other field coil.

5. In an externally excited generator, a generating winding, two externally excited field coils, means for alternately conducting magnetic flux from one exciting coil in one direction through the generating winding and for conducting magnetic flux from the other field coil in the reverse direction through the generating winding, and series electrical connections for said coils where-

by the decline of magnetic flux through one field coil boosts the current flowing through the other field coil.

6. In an externally excited generator, a generating winding, two externally excited field coils, stator magnetic members for said field coils, means for alternately conducting magnetic flux from one exciting coil in one direction through said generating winding and for conducting magnetic flux from the other field coil in the reverse direction through the generating winding, means for short circuiting the magnetic circuits of both coils simultaneously between the periods of flux reversal, and electrical connections for said field coils so arranged that the decline of the magnetic flux through one field coil boosts the current flowing through the field coil having its magnetic circuit closed through the generating winding.

7. In an externally excited generator, a generating winding with a magnetic core, two externally excited field coils, cores for the field coils having similar poles magnetically connected to respective ends of the core of the generating winding, a rotor adapted to magnetically connect a pole of the core of one field coil to a diametrically opposite pole of the core of the other field coil, whereby the magnetic flux through one field coil is first conducted in one direction through the generating winding and then the magnetic flux from the other field coil is conducted in reverse direction through the generating winding, and electrical connections between said field coils so arranged that the decline in the magnetic flux through one field coil boosts the current flowing through the other field coil during the period that the magnetic circuit of the second field coil is closed through said generating winding.

8. In a magneto, an unmagnetized rotor, a generating winding having a core, polepieces attached to each end of said core and having pole faces positioned above the horizontal median of said rotor, externally excited field coils having cores magnetically connected to each polepiece in like polarity relation, and other pole faces positioned below said horizontal median and having a magnetic polarity opposite that of said first mentioned pole faces, means including said rotor for alternately closing the magnetic circuit from one field coil through the generating winding and opening a magnetic circuit from the other field coil, and electrical connections between said coils so arranged that the current generated by the decline of magnetic flux through one field coil boosts the current flowing through the other field coil.

9. In an externally excited generator, a generating winding, externally excited field windings, electrical connections between said field windings, means including a rotor for closing the magnetic circuit from a part of the field winding through the generating winding and simultaneously opening the magnetic circuit from another part of the field winding and subsequently closing the magnetic circuit which was previously open and opening the magnetic circuit which was previously closed, said electrical connections between said field windings being so arranged that a decrease in magnetic flux in the open magnetic circuit of one part of the field winding induces a current which augments the current in that part of the field winding having its magnetic circuit closed through the generating winding.
